SCHOOL SAFETY TRAFFIC SIGN

John A. Dey, Miami, Fla.

Application March 1, 1951, Serial No. 14,351

Term of patent 7 years

(Cl. D72—1)

To all whom it may concern:

Be it known that I, John A. Dey, a citizen of the United States of America, residing at Miami, county of Dade, State of Florida, have invented a new, original, and ornamental Design for a School Safety Traffic Sign, of which the following is a specification, reference being had to the accompanying drawing, forming a part hereof.

In the drawing:

Fig. 1 is a front elevational view of a school safety traffic sign, showing my new design;

Fig. 2 is a rear elevational view thereof; and

Fig. 3 is a side elevational view.

The dotted lines shown in the drawing are for illustrative purposes only.

I claim:

The ornamental design for a school safety traffic sign, substantially as shown and described.

JOHN A. DEY.
